Primary Examiner — Steven J Czyz(74) *Attorney, Agent, or Firm* — Dunlap Bennett & Ludwig, PLLC; Anna L. Kinney(57) **CLAIM**

The ornamental design for a tampon case, as shown and described.

DESCRIPTION

FIG. 1 is a top front perspective view of a tampon case showing my new design;

FIG. 2 is a front elevation view thereof, the rear elevation view being a mirror image thereof;

FIG. 3 is a right elevation view thereof;

FIG. 4 is a left elevation view thereof;

FIG. 5 is a top elevation view thereof;

FIG. 6 is a bottom elevation view thereof; and,

FIG. 7 is a top front perspective view thereof, shown in a closed position.

The broken lines shown in the drawings depict portions of the article that form no part of the claimed design.

1 Claim, 5 Drawing Sheets(56)
